UNITED STATES PATENT OFFICE.

LOUIS COURTOT, OF PARIS, FRANCE, ASSIGNOR TO AMERICAN RADIATOR COMPANY, OF NEW YORK, N. Y., A CORPORATION OF NEW JERSEY.

PANEL BOILER FOR LOW-PRESSURE-STEAM HEATING.

Application filed May 31, 1922, Serial No. 564,713, and in France June 18, 1921.

My invention relates to a boiler of the water tube type with suitable circulation of water and gases of combustion which is intended for heating by steam at low pressure or by hot water, and is constructed of cast iron panels whereby an inexpensive and simplified construction is obtained.

Each of the said panels consists of a cast iron plate having formed therein a set of parallel conduits of small cross-section as well as transverse canals connecting the ends of the said conduits together with connecting apertures disposed upon said transverse canals in order to connect the plates together or to outer steam or water conduits. A plate of this kind may be considered as being composed of a set of parallel tubes connected together by intermediate ribs and by transverse main tubes, the whole being cast in one piece.

According to my invention, it is feasible to construct boilers of a considerable capacity comprising the drum and elements of small size and light weight, which have great strength and are constructed with facility, whereas the known sectional boilers are composed, for the large sizes, of heavy and bulky pieces which offer a great risk of breakage and are difficult to manufacture.

In the boilers according to this invention, plates of uniform construction and varying only in number, are employed for the construction of boilers whose heating surface and resulting capacity may differ within wide limits.

The accompanying drawing shows by way of example in lengthwise, transverse and horizontal section various constructional forms of boilers according to the invention, wherein:

Figs. 1, 2 and 3 relate to a boiler having a furnace and a main body of brickwork.

Figs. 4, 5 and 6 relate to a boiler without brickwork.

Fig. 1 is a vertical section on the line 1—1, Fig. 2.

Fig. 2 is a partial vertical section on the line 2—2, Fig. 1.

Fig. 3 is a half plan view in section on the line 3—3, Fig. 1.

Fig. 4 is a vertical section on the line 4—4, Fig. 5.

Fig. 5 shows to the left a half vertical

section on the line 5—5, Fig. 4, and to the right a half-vertical section on the line 5'—5' of the same figure.

Fig. 6 is a half plan view in section on the line 6—6, Fig. 4.

In Figs. 1, 2 and 3, the boiler therein represented has been constructed in order to provide for the maximum facility of manufacture at a minimum cost. It comprises two groups whereof each is composed of a cast iron drum 1 and two sets of four panels 2 and 3 connected together and communicating with the drum at the front by the necks 4 and in the rear by the tubes 5. Each pair of panels 2 and 3 is independent of the others and communicates individually with the drum; the water circulation takes place in one plane and without a complicated path; the water descends directly from the drum through the rear tubes 5 and rises through the front tubes 4 after traversing the panels 2 and 3. The circulation of the hot gases will preferably take place in contrary direction to the water circulation, but this is not essential. It is preferable to dispose a steam separator 6 in the drum 1 at the steam outlet.

The drum 1 is suspended from the supports 7 by the straps 8 as carried out in certain water tube boilers, and the tube elements are suspended directly from the drum without any other means of support, so that all parts of the boiler are enabled to expand freely whereby any stresses tending to cause leakage or breaking will be obviated. Should the capacity of the drum be insufficient, it will be an easy matter to substitute for the steam header 9 a supplementary steam chamber. On the other hand, in the case of hot water boilers, the diameter of the drums 1 may be very small, and each of these may support a single tubular plate in place of several plates.

In Figs. 4, 5 and 6, the construction of the boiler differs from that of Figs. 1 to 3. In the first place, the upper part is no longer composed of cylinders of cast iron or plate iron disposed parallel to each other and lengthwise of the boiler, but is formed of the cast iron sections 10 analogous to the ones employed in sectional boilers. The said sections are connected together by two apertures 21 of large diameter so as to facilitate

the circulation of water and steam there-through. They have a suitable moulded shape at the edges and at the ribs for strengthening the bottom. The said sections are disposed upon an iron frame of double T-iron 22.

The number of panels 2 and 3 will vary according to the requisite heating surface, and the sections 10 may be made in any 10 desired size for a given number of pairs of panels and the desired heating surface. The panels 2 and 3 are suspended from a front section 10 by necks 4, and at the rear are supported by the conduit 13.

15 In the second place, the brickwork can be eliminated in this type, and the sides of the boiler are constituted by tubular panels 11 connected at the top with each section 10, and at the bottom with a main side 20 conduit 12; the latter is connected with a main rear conduit 13 which communicates with the panels 3 and the water descent tubes of the sections 10. The panels 11 are all 25 of uniform construction and can be moulded with facility. If necessary, each one of the said panels can be replaced without interfering with the others, even should the boiler form part of a battery. In this case, the upper connection of the panel 11 which 30 requires to be replaced is dismounted from the outside, whilst the lower connection is dismounted from the inside of the ash pit. The front plate is faced with firebrick on the inside corresponding to the furnace portion. Certain portions of the rear end may 35 also be lined with brick on the inside, but a heat insulating lining will suffice as a general rule. The top and sides of the boiler are provided with a heat insulating covering 40 as in the sectional boilers.

By varying the dimensions of the top sections and the number of pairs of panels 2 and 3, any desired size of boiler can be obtained; the panels 2, 3 and 11 will remain 45 the same for all sizes, and only the top sections and a few flat pieces will be different.

The boiler shown in Figs. 1, 2 and 3 may also be constructed with a top analogous 50 to the one shown in Figs. 4, 5 and 6. A combined construction may also be used wherein the various cast iron elements or drums are replaced by a single cylindrical

drum or a plurality of parallel cylindrical drums constructed of iron or steel plate, 55 whilst the tubular portion is composed, as before, of cast iron panels. The drum or drums might also be disposed transversely to the plane of the heating panels 2, 3, 11 instead of parallel to the latter. Inspection 60 and cleaning of the panels forming the tube sets is much facilitated by the apertures provided for the purpose, as shown in the drawings. The grate has a sufficient size 65 to dispense with very frequent cleaning, and means may be readily employed to afford a larger size for the grate should this be desired. The furnace is disposed so that a certain thickness of combustible can be fed in, when coke or anthracite are used. 70

Should it be necessary to replace one of the panels for any reason, this may be very readily carried out without interfering with the adjacent pairs of panels or the brick-work. The said boilers are very well adapted 75 for installation in batteries. The arrangement of the furnace provides for the use of mechanically operated grates, and this may be advantageous in large plants. In the boilers herein represented, all the 80 joints are visible and quite accessible.

I claim:

1. A boiler comprising a drum, and a plurality of pairs of vertical water heating panels disposed below said drum and communicating therewith, each panel consisting of a set of parallel tubes and tubes transversely thereof cast in one piece, the panels of each pair being alined at the front and rear of the boiler respectively and being 85 communicatively connected, the front panels being arranged with the parallel tubes thereof inclined and the rear panels being arranged with the parallel tubes thereof vertical, substantially as specified. 95

2. A boiler comprising a drum, vertically arranged front and rear water heating panels disposed below said drum and communicating therewith and with each other, said rear panel comprising a set of vertically 100 arranged parallel tubes and said front panel comprising a set of horizontally arranged parallel tubes, substantially as specified.

In testimony that I claim the foregoing as my invention, I have signed my name.

LOUIS COURTOT.
